UNITED STATES PATENT OFFICE.

CORNELIUS S. CLARK, OF NORFOLK, VIRGINIA, ASSIGNOR OF ONE-FOURTH TO WM. H. VENABLE AND EDWIN S. ELY, BOTH OF NORFOLK, VIRGINIA.

RAIL-CHAIR.

1,342,251.

Specification of Letters Patent.

Patented June 1, 1920.

Application filed January 8, 1920. Serial No. 350,076.

To all whom it may concern:

Be it known that I, CORNELIUS S. CLARK, a citizen of the United States, residing at Norfolk, in the county of Norfolk and State 5 of Virginia, have invented new and useful Improvements in Rail-Chairs, of which the following is a specification.

This invention relates to combined railway rail-joints and chairs adapted to seat 10 and join the abutting ends of railway rails.

The objects are to provide a rail chair and joint which will firmly support the rails in position, which is adapted to straddle a cross-tie, or which may be positioned between two of the cross-ties to which the rails are secured, which has relatively few parts, 15 which may be easily and expeditiously placed in position, and which, when used to connect rails which carry a current of electricity insures at all times a perfect electrical connection between such rails.

With these and other objects in view, my invention consists in certain features of structure, combination and relation which 20 will be more fully set forth hereinafter.

I have illustrated what I now consider to be the preferred form of my invention in the accompanying drawings, wherein:

Figure 1 is a plan view of a section of a 30 rail with my improved chair attached.

Fig. 2 is a side elevation of my improved chair-supporting a rail.

Fig. 3 is a transverse section taken on line 3-3 of Fig. 2.

Fig. 4 is a section taken on line 4-4 of 35 Fig. 1, the rail being removed.

Fig. 5 is a perspective view of one of the wedging plates.

Fig. 6 is a detail of a metal joining and 40 conducting strip.

Referring to the drawings wherein similar numerals designate like parts throughout the several views:

My improved rail chair and joint comprises a body 1 adapted to join and support 45 rails 2. This chair is provided with a longitudinal channel 3 and a slot 4 through the top thereof on the line of its longitudinal axis, the slot being in communication with 50 the channel 3 and adapted to receive the web of a rail. The bed of channel 3 is inclined downward in opposite directions from the approximate longitudinal center of the chair, as indicated at 5. A strip 6 of relatively soft metal which is a good conductor 55

of electricity and preferably a separate removable part or which may be in the form of a facing, or an insertion, serves to secure the rail in position and also to insure a perfect electrical connection between the rails 60 when they are used to carry an electrical current. The external upper face of the chair is provided with longitudinal flanges 7.

The rails are secured together by means of fish-plates 8 which have their inner faces 65 recessed as at 9 to take over the flanges 7 of the chair. The fish-plates are secured to the rail by means of usual bolts 10.

To secure the rails in position in the chair wedge plates 11 are provided. These plates are formed with flat upper surfaces 12 adapted to support a rail. The under faces of the plates are beveled, as indicated at 13, to coöperate with the inclined bed of the chair channel to wedge the rails in position. 70 These wedge plates have lugs 14 projecting on both sides of one end, which lugs are formed with apertures 15. The wedge plates are secured in the chair by means of bolts 16 which extend through lugs 13 and 75 carry nuts 17. These bolts extend the length of one side of the chair passing through the two sets of lugs and by turning the nuts on the ends of the bolts the wedge plates are drawn toward each other, thereby 80 wedging the rails in position.

In the operation of the device constructed in accordance with my invention, the rails are placed in position in the chair, the web of the rail occupying the longitudinal slot, 90 and the abutting ends of the rails being about midway the length of the chair. The rails are lifted and suspended in the chair, the fish-plates bolted to the rails, the wedge plates are inserted in both ends of the chair 95 beneath the bottom flanges of the rails, the bolts inserted through the lugs, and the nuts screwed on and turned until the rails are securely held. As the nuts are turned it will be seen that the upper faces of the lower 100 flanges of the rails will be forced into the soft metal strip constituting the upper lining of the channel, thereby securing the rails against longitudinal movement and securing perfect electrical connection between the 105 rails.

Having described my invention, I claim as follows:

1. A combined rail chair and joint comprising a chair formed with an internal 110

channel, said channel having its bed inclined to provide two surfaces, beveled wedge plates adapted to coöperate with the inclined bed of said internal channel to secure 5 the rail in position; said wedge plates being formed with projecting apertured flanges and means to secure said wedge plates in position in the chair.

2. A combined rail chair and joint comprising a hollow chair having a longitudinal slot through its upper face, the main floor of said chair having downward and oppositely extending inclined faces from the approximate longitudinal center of the chair 10 and means whereby rails may be wedged into position relative to the chair and relative to one another.

3. A combined rail chair and joint comprising a chair having a longitudinally disposed internal channel, a slot through the upper face of said chair communicating with said channel and adapted to receive the web of a rail, a strip of relatively soft metal adapted to line the upper wall of said channel 20 and means whereby the rails may be wedged into position relative to one another and to the chair.

4. A combined rail chair and joint comprising a chair having a longitudinally disposed internal channel, a slot through the upper face of said chair communicating with said channel and adapted to receive the web of a rail, a strip of relatively soft metal adapted to line the upper wall of said channel 30 and means whereby the rails may be secured in position in the chair.

5. A combined rail chair and joint comprising a chair having a longitudinally disposed internal channel, a slot through the

upper face of said chair communicating with said channel and adapted to receive the 45 web of a rail, a strip of relatively soft metal lining the upper wall of said channel, the bed of said channel being formed with downward, oppositely extending inclined faces from the approximate longitudinal 50 center of the chair, beveled wedge plates having apertured ears and bolts coöperative with said apertured ears for securing the wedge plates in position.

6. A combined rail chair and joint comprising a chair having a longitudinally disposed internal channel, a slot through the upper face of said chair communicating with said channel and adapted to receive the web of a rail, a strip of relatively soft metal 55 lining the upper wall of said channel, the bed of said channel being formed with downward, oppositely extending inclined faces from the approximate longitudinal 60 center of the chair, and means whereby the rails may be secured in position in the chair.

7. A rail chair and joint comprising in combination a chair having a longitudinal channel extending therethrough and a longitudinal slot through the upper face thereof, upward extending flanges on the upper face of said chair, fish-plates adapted to secure the abutting ends of rails together, said fish-plates having their inner faces recessed so as to coöperate with the flanges on 70 said chair, and means including beveled wedge plates whereby the rails may be secured in position in the chair.

In testimony whereof I have hereunto set my hand in presence of two subscribing witnesses.

CORNELIUS S. CLARK.
